MACHINE FOR USE IN THE MANUFACTURE
OF SHOESCorwin W. Baker, Beverly, Mass., assignor to
United Shoe Machinery Corporation, Flemington, N. J., a corporation of New Jersey

Application March 21, 1947, Serial No. 736,169

18 Claims. (Cl. 12—14)

1 This invention relates to machines for use in the manufacture of shoes, and is herein shown as applied to a power-operated toe-lasting machine constructed in many respects as disclosed in United States Letters Patent No. 2,160,846, granted on June 6, 1939, on an application of F. C. Eastman and A. F. Pym, but embodying certain features disclosed in Letters Patent No. 2,380,407, granted on July 31, 1945, on an application of P. E. Burby, and in other Letters Patent hereinafter mentioned. As will be evident, however, the invention is not limited to machine organizations of that particular character or to lasting machines.

In the above-mentioned machine the shoe is positioned by means which engages the bottom face of the forepart of the insole and against which it is clamped by a toe rest engaging the upper at the top of the forepart, the toe rest being moved into clamping position substantially at the beginning of a cycle of operations of the machine. In the course of the cycle of operations the marginal portion of the upper about the toe end of the last is wiped inwardly over the insole by toe-embracing wipers. At a predetermined time in the cycle the wipers are moved a short distance heightwise of the last to apply a final increased pressure to the overwiped upper, and at substantially the same time the toe rest is pressed more forcibly against the shoe to support it firmly against the increased pressure thereon. To insure that the toe rest at this time will not make an impression in the upper which will be visible in the finished shoe, it is desirable that it engages the upper uniformly over as great an area as possible. The present invention provides a construction especially well adapted for this purpose. As herein shown, the toe rest comprises a container which incloses a mass of granular material of the character hereinafter described and which has a flexible and extensible wall arranged to conform itself to the contour of the shoe with accompanying displacement of a portion of the mass of granular material when the toe rest is first applied to the shoe. That is, the toe rest readily shapes itself to the shoe over a large area, regardless of the style or size of the shoe, when it is first pressed against it. To cause it thereafter to support the shoe firmly as required when the wipers increase their pressure on the shoe, further displacement or deformation of the mass of granular material by the increased pressure of the shoe thereon is prevented by producing a partial vacuum in the container; that is, by exhausting some of the air intermingled with

2 the mass of granular material. The result of this procedure is that the atmospheric pressure on the outside of the flexible wall of the container prevents such increase in volume of the mass of granular material as would necessarily result, in accordance with the well-known principle of dilatancy, from any further deformation of the mass, such pressure holding the grains of the mass tightly interlocked in frictional engagement with one another. The mass of granular material thus becomes substantially rigid. To produce the partial vacuum in the container the machine herein shown is provided with a suction pump which is automatically started in operation after the toe rest has conformed to the contour of the shoe but before its pressure on the shoe is increased as above described.

The novel features of the invention will now be more particularly described with reference to the accompanying drawings and thereafter pointed out in the claims.

In the drawings,

Fig. 1 is a perspective view of the greater portion of the front and right-hand side of the machine to which the invention is herein shown as applied;

Fig. 2 is a view partly in right-hand side elevation and partly in section, showing the toe rest and the means for applying it to the shoe;

Fig. 3 is a section on the line III—III of Fig. 2; Fig. 4 is a section on the line IV—IV of Fig. 2; Fig. 5 is a view partly in right-hand side elevation and partly in section, showing the toe rest in clamping relation to the shoe and showing also a portion of the toe-lasting means;

Fig. 6 is a view partly in front elevation and partly in section of parts shown in Fig. 5; and

Fig. 7 is a cam chart illustrating the timing of such operations of the machine as are of interest with reference to the present invention.

In view of the disclosures in the above-mentioned Letters Patent and in others hereinafter mentioned, only such portions of the machine are herein shown and will be described in detail as it is necessary to refer to for an understanding of the invention. The position of the shoe, herein shown as one of the welt type, is determined by means constructed substantially as disclosed in Letters Patent No. 2,385,414, granted on September 25, 1945, on an application of E. A. Holmgren, as illustrated in Figs. 5 and 6. Briefly, such shoe-positioning means comprises three pins 2 rigidly supported by a block 4 and arranged to engage the bottom face of the forepart of the insole to determine the position of the shoe heightwise and

with respect to tipping movements, and a plate 6 having a downwardly extending flange 8 which engages the inner face of an upstanding lip α on the insole about the end and along the sides of the toe to position the shoe lengthwise and laterally. The plate 6, when the shoe is in position to be operated on, is held down on the insole by three spring-pressed pins 10, two of which are visible in Fig. 5. Substantially at the beginning of a cycle of automatic operations of the machine, initiated by the tripping of a clutch (not shown), the shoe is clamped against the lower ends of the pins 2 by upward movement of a toe rest 12 the construction of which will be hereinafter described. While the shoe is thus held by the toe rest a pair of cam-operated wipers 14 (Figs. 1 and 5) which embrace the upper about the toe end of the last are moved upwardly to wipe the upper heightwise of the last and are thereafter advanced bodily lengthwise of the last and closed inwardly widthwise of the last to wipe the marginal portion of the upper over the feather and against the lip α of the insole. In the course of this toe-lasting operation the upper is further controlled by a retarder 15 (Fig. 1) which clamps the upper on the wipers in accordance with the disclosure of the above-mentioned Letters Patent No. 2,380,407, this retarder being used in place of the upper-pulling grippers shown in Letters Patent No. 2,160,846.

The toe rest 12 is supported on the upper end of a rod 16 vertically movable in bearings in the frame of the machine, this rod, as herein shown, being operated and controlled by mechanism constructed substantially as disclosed in Letters Patent No. 2,224,146, granted on December 10, 1940, on an application of F. C. Eastman. For a better understanding of the present invention this mechanism will now be described. For lifting the rod 16 to apply the toe rest to the shoe there is provided a yoke 18 (Fig. 2) slidably mounted at its lower end on the rod and at its upper end on a sleeve 20 through which the rod extends. The yoke 18 is raised and lowered by a pair of crank arms 22 fast on a cam-operated rockshaft 24 and connected to the upper end of the yoke by a pair of links 26. When the yoke is raised it acts on the rod 16 through one of the other or both of two springs 28, 30 of different strengths as determined selectively by the operator and also through a disk 32 integral with the previously mentioned sleeve 20 and engaging a shoulder 34 formed on the lower end of an enlarged portion of the rod 16. The lower ends of both springs 28 and 30 rest on a washer 36 which is supported by nuts 38 threaded on the lower end of a sleeve 40 (Fig. 3) slidably mounted on the rod 16. At their upper ends the springs 28 and 30 are in engagement respectively with concentric rings 42 and 44 (Figs. 2 and 4) which are relatively movable vertically. The ring 42 has fast thereon three upwardly extending pins 46 and the ring 44 is similarly provided with three upwardly extending pins 48. Formed in the disk 32 are three holes 50 arranged to aline with the pins 46 when the disk is in one position with respect to turning movement, as shown in Fig. 4, and three other holes 52 arranged to aline with the pins 48 when the disk is in another position, the disk and its sleeve 20 being rotatable about the rod 16 into one or the other of these two positions or into a third position in which neither of the two sets of holes is in alinement with the corresponding pins. Through means hereinafter described the sleeve 40 and the washer 36 are raised by the upward

movement of the yoke 18, and it will be evident that in accordance with the adjustment of the disk 32 one or the other or both of the springs 28, 30 are rendered effective in response to this movement to raise the rod 16 and the toe rest 12 by reason of engagement of the upper ends of the appropriate pins with the disk 32 which engages the shoulder 34 on the rod. Adjustment of the disk 32 selectively to its different positions is effected by turning the sleeve 20 about the rod 16 by the operation of mechanism not herein shown but of the same construction as mechanism disclosed in Letters Patent No. 2,160,846 for turning a corresponding sleeve. To maintain the two sets of pins 46 and 48 always in proper relation to each other and to the holes in the disk 32, there is formed integral with the upper end of the sleeve 40, above the rings 42 and 44, a disk 54 provided with holes through which all the pins extend, this disk being adjustably controlled by two setscrews 56 which are threaded in the yoke 18 and bear respectively on opposite sides of a lug 58 on the disk.

As also disclosed in Letters Patent No. 2,224,146, the construction shown is further such that neither of the springs 28 or 30 is compressed by that upward movement of the yoke 18 whereby the toe rest is applied to and pressed against the shoe prior to the lasting operation, although one or the other or both of these springs serve as above described as means through which the toe rest is thus raised and applied to the shoe. For pressing the toe rest yieldingly against the shoe at this time by the upward movement of the yoke there is provided another spring 60 which is lighter than either of the springs 28 or 30. At its upper end the spring 60 bears on a flange 62 formed on a sleeve 64 which is slidably mounted on the rod 16 and abuts against the lower end of the sleeve 40. At its lower end the spring 60 bears on a disk 66 which is fast on the upper ends of two rods 68, the lower ends of these rods being fast in a block 70 which rests on a shoulder 72 on the lower end portion of the yoke 18. A lug 74 on this block lies in a recess in the yoke to prevent the block from turning. It will thus be seen that when the yoke is raised it acts through the block 70 and the rods 68 to raise the disk 66, and this disk acts through the comparatively light spring 60 to raise the two springs 28 and 30 through one or the other or both of which upward movement is imparted to the rod 16 and the toe rest in the manner above described. When the toe rest meets the resistance of the shoe the spring 60 is compressed more or less by continued upward movement of the yoke 18, the block 70 and the rods 68 without compression of either of the heavier springs 28, 30. The shoe is accordingly supported by the force of the comparatively light spring 60, and it continues to be so supported as the wipers 14 are operated to wipe the marginal portion of the upper inwardly over the insole.

At a predetermined time in the cycle of operations, as more fully hereinafter explained, the wipers are moved downwardly a short distance to increase their pressure on the overwiped upper and the yoke 18 is moved farther upwardly to increase the supporting pressure of the toe rest on the shoe. In order to support the shoe firmly enough against the increased pressure of the wipers on the upper, the construction is such that force is transmitted at this time from the yoke 18 to the sleeve 64 positively, instead of yieldingly through the spring 60, so that the greater force

of one or the other or both of the two springs 28, 30 is effective on the toe rest. For this purpose there is threaded on the lower end of the sleeve 64 a block 76 having on its opposite sides downwardly directed ratchet teeth 78 arranged to be engaged by a pair of pawls 80 which are pivotally mounted at their lower ends on rods 82 supported in the opposite ends of a pair of plates 84 at the opposite sides of the block 70. These plates are pivotally mounted midway between their opposite ends and midway between the pawls on studs 86 formed on the block 70. A spring 88 connected to the two pawls 80 tends to swing them inwardly toward the ratchet teeth 78. Initially, however, the pawls are held out of engagement with the ratchet teeth by a cam block 90 slidably mounted on one of the rods 82 and having on its opposite sides cam faces 92 arranged to control the pawls by engagement with their upper ends. A spring 94 mounted on the rod 82 below the cam block 90 holds the block initially up-raised in such a position, determined by its engagement with the disk 66, that the pawls are held out of engagement with the ratchet teeth, thus permitting compression of the spring 60 by the upward movement of the yoke 18, as hereinbefore described. The cam block at this time moves upwardly with the yoke and the block 70 and it continues to hold the pawls out of engagement with the ratchet teeth as the wipers wipe the upper inwardly over the insole. To cause the pawls thereafter to engage the ratchet teeth the cam block 90 is moved downwardly against the resistance of the spring 94 by downward movement of a rod 96 which extends through an opening in the block and carries a collar 98 arranged to engage the upper face of the block. This rod is pivotally connected at its upper end to an arm 100 (Fig. 2) fast on a rock-shaft 102 operated by a cam (not shown), as more fully disclosed in Letters Patent No. 2,224,146. By reference to Fig. 3 it will be seen that initially there is sufficient space between the cam block 90 and the collar 98 to permit such upward movement of the block as occurs when the toe rest is applied to the shoe through the spring 60. At the proper time in the cycle downward movement is imparted to the rod 96 to move the block 90 downwardly and thus to cause the pawls 80 to engage the ratchet teeth 78. It will be evident that when the pawls are thus in engagement with the ratchet teeth any further upward movement of the yoke 18 or any depression of the shoe and the toe rest by the pressure of the wipers on the shoe results in compression of one or the other or both of the springs 28, 30, depending upon the adjusted position of the disk 32.

Further to insure that the toe rest 12, while supporting the shoe firmly enough against the final increased pressure of the wipers on the upper, will not make any impression in the top of the forepart of the upper which will be visible in the finished shoe, the toe rest herein shown, for purposes of the present invention, comprises a hollow rubber container 104 provided with a flexible and extensible wall and secured by cement on the top of a holder 106 mounted on the upper end of the rod 16, the rubber container having therein a mass of granular material 108 which, together with the wall of the container, conforms to the contour of the top of the forepart of the shoe over a large area in response to pressure of the shoe thereon when the toe rest is forced yieldingly against the shoe through the spring 60.

Mingled normally with the mass of granular material and occupying such space in the container as is not occupied by the material is atmospheric air. The invention is not limited to the use of any special granular material or to the use of material the particles of which are of any particular size or shape, but material which has been used successfully for the purpose in view consists of aluminum oxide the particles of which are similar to grains of fine sand. To render this toe rest firm enough to support the shoe as required after it has thus conformed to the contour of the shoe, the invention further provides means for producing a partial vacuum in the container 104 before the increased pressure is applied to the shoe by the wipers. For this purpose there is supported on a bracket 110 on the frame of the machine a rotary suction pump 112 operated by an electric motor 114. The pump communicates through a filter 116 and a flexible tube 118 with a short metal tube 120 which is fast on a block 122 on the toe rest holder 106 and is in communication with the interior of the container 104 through a screen 124 which prevents escape of the granular material 108. Initially the motor 114 is at rest, so that there is atmospheric pressure in the container 104 when the toe rest is applied to the shoe. To start the motor and thus to cause the pump 112 to produce a partial vacuum in the container there is provided an electrical switch 126 (Fig. 3) mounted in a switch box 128 which is supported on a block 130 fast on one side portion of the yoke 18. A spring arm 131 carrying one of the contact members of the switch 126 is controlled by a pin 132 slidably mounted in the switch box 128 and engaged at its lower end by a lever 134 pivotally mounted at 136 on a block 138 secured to the yoke 18 at the opposite side of the yoke from the block 130. A spring 140 connected to the lever 134 and to the block 130 tends to swing the lever upwardly and causes the lever to hold the switch 126 normally open. The switch is closed to start the motor in response to the downward movement of the pawl-controlling block 90 effected as hereinbefore described by downward movement of the rod 96 before the increased pressure is applied to the shoe by the wipers. For this purpose an arm 142 extending from the lever 134 in angular relation thereto is provided with a screw 144 arranged to be engaged by the lower face of the block 90 when the block is moved downwardly. The partial vacuum thus produced in the container by the pump has the effect of preventing further deformation of the mass of granular material by the increased pressure of the shoe thereon, since the atmospheric pressure on the wall of the container prevents such expansion in bulk of the mass of material as would necessarily result, in accordance with the principle of dilatancy, from any further deformation of the mass. The grains of the mass of material are also pressed firmly together in frictional engagement with one another by the atmospheric pressure on the container. The degree of vacuum produced by the pump is such that the mass of granular material thus becomes substantially rigid against such pressure as is applied thereto by the shoe.

It will be understood that in the return of the parts to starting positions the switch 126 opens automatically to stop the motor and the pump. In order to relieve promptly the partial vacuum in the container at this time the short metal tube 120 is in communication with a passage 146 formed in the block 122 and controlled by a valve

148. This valve comprises a small lever 150 pivotally mounted between its ends on the block 146 and having thereon a pad 152 for closing the lower end of the passage 146. A spring 154 acting on the lever holds the valve in closed position (Fig. 5) when the pump 112 is operated. When the toe rest is moved downwardly in the return of the parts to starting positions a pin 156 mounted in a member 158 on the top of the frame 160 of the machine engages the lever 150 and 10 opens the valve to relieve the partial vacuum in the container, as shown in Fig. 2.

The manner of operation of the machine, in so far as it is of interest with reference to the present invention, will now be briefly summarized with reference to the cam chart (Fig. 7). The operator presents the shoe to the machine with the toe end of the insole in engagement with the flange 8 of the plate 6, this flange engaging the inner face of the lip of the insole, and then starts the machine by tripping the clutch. At the beginning of the cycle of operations upward movement is imparted to the yoke 18 which controls the toe rest 12, and by this movement of the yoke the toe rest is moved upwardly to clamp the shoe 25 against the pins 2, the plate 6 being lifted by the shoe against the resistance of the spring-pressed pins 10. The toe rest is thus forced against the shoe yieldingly by compression of the comparatively light spring 60, and in response to the pressure of the shoe thereon the rubber wall of the container 104 and the mass of granular material 108 therein conform to the contour of the shoe over a large area. The wipers 14 then operate on the shoe, their movements being substantially as disclosed in Letters Patent No. 2,160,846. That is, after being preliminarily advanced and closed about the toe below the edge of the shoe bottom they are moved upwardly to wipe the toe end of the upper heightwise of the last, i. e., to perform what is commonly known as the upwiping operation after which they are further advanced and closed to wipe the marginal portion of the upper inwardly over the feather and against the lip of the insole. During this wiping operation the toe rest remains under control of the comparatively light spring 60. After the wipers have thus wiped the upper inwardly, the machine comes to a stop at 190° of the cycle to permit the operator to fasten a binder wire to the shoe at one side of the shoe bottom and to pull the wire inwardly against the shoe under the wipers. He then starts the machine again, whereupon the wipers are slightly lifted and are partially retracted and opened to permit the operator to pull the wire farther inwardly against the upstanding margin of the upper opposite the lip of the insole. Thereafter, the wipers are again fully advanced and closed to press the upstanding margin of the upper against the lip of the insole and to press the wire against the upper and are moved downwardly to the same level as in first wiping the upper inwardly over the insole. When these advancing and closing movements of the wipers have been nearly completed, and thereafter, the wipers are moved still farther downwardly, between 245° and 270° of the cycle, to increase their pressure on the overwiped portion of the upper, and at substantially the same time the yoke 18 is moved farther upwardly to increase the supporting pressure of the toe rest on the shoe. In this upward movement of the yoke it acts on the toe rest, not through the spring 60, but through one or the other or both of the heavier springs 28, 30, since prior to the

beginning of its upward movement the block 90 is moved downwardly by the rod 96 to cause the pawls 80 to engage the ratchet teeth 78 of the block 76. As indicated on the chart, the rod 96 thus receives its downward movement between 205° and 240° of the cycle. In response to the downward movement of the block 90 also the lever 134 is operated to cause the switch 126 to close, thus starting the motor 114 and the pump 112 to exhaust air from the container 104 and thereby to produce a partial vacuum in the container. In this manner the mass of granular material 108 is caused to become substantially rigid, as hereinbefore explained, so that the toe rest will support the shoe firmly against the final increased downward pressure of the wipers thereon. Since the wall of the container and the mass of granular material have previously conformed to the contour of the shoe over a large area, there is no substantial danger that the toe rest in its increased pressure on the shoe at this time will form in the upper any impression which will be visible in the finished shoe.

After the shoe has been subjected to the increased pressure of the wipers as above described the machine again comes to a stop at 270° of the cycle to permit the operator to fasten the binder wire at the other side of the shoe. Thereafter the operator again starts the machine, whereupon the parts are returned to their starting positions. In the course of such return of the parts the switch 126 is opened by the lever 134 in response to upward movement of the block 90 to stop the operation of the pump. To relieve promptly the partial vacuum in the container 104 the valve 148 is opened by engagement of the pin 156 with the lever 150 substantially at the end of the downward movement of the toe rest. This leaves the wall of the container 104 and the mass 40 of granular material therein ready to conform to the contour of the next shoe in the operation of the machine thereon.

While the invention is herein disclosed as applied to means for supporting a shoe at the top of the forepart against pressure on the bottom thereof, it should be understood that it is more generally applicable to various uses in relation to shoes in shoe machines. It is also to be understood that the invention is not limited to a construction in which the means for reducing the pressure in the container consists of a pump which is started in every cycle of operations of the machine. It will further be evident that the results obtained are not dependent upon the use 55 of air or other gaseous medium intermingled with the granular material, but that a liquid, such as water, might be used instead. Accordingly, in the appended claims the term "fluid" is used as applicable to either a gaseous or a liquid medium.

Having described the invention, what I claim as new and desire to secure by Letters Patent of the United States is:

1. In a shoe machine, a container inclosing a deformable mass of granular material mingled with a fluid and having a flexible and extensible wall impervious to fluid, means for causing said wall of the container to conform to the contour of a portion of a shoe on a last with accompanying deformation of the mass of granular material 65 and thereafter to press more forcibly on the shoe, and means for reducing the pressure of the fluid in the container after said wall has thus conformed to the shoe but prior to such increase of pressure on the shoe to prevent further deformation 70 of the mass of granular material.

75

2. In a shoe machine, a container inclosing a deformable mass of granular material mingled with a gaseous fluid and having a flexible and extensible wall impervious to fluid, means for causing said wall of the container to conform to the contour of a portion of a shoe on a last with accompanying deformation of the mass of granular material and thereafter to apply increased pressure to the shoe, and means for producing a partial vacuum in the container after said wall has thus conformed to the shoe but prior to such increase of pressure on the shoe to render the mass of granular material substantially rigid when the increased pressure is applied.

3. In a shoe machine, a container inclosing a deformable mass of granular material mingled with a fluid and having a flexible and extensible wall impervious to fluid, means for effecting relative movement between said container and a shoe in the machine to cause said wall of the container and the mass of granular material to conform to the contour of a portion of the shoe in response to pressure of the shoe thereon and for thereafter increasing the pressure of the shoe on said wall in the course of a cycle of operations of the machine, and automatic means for reducing the pressure of the fluid in the container at a time in the cycle after said wall has thus conformed to the shoe but prior to the increase of pressure of the shoe thereon to prevent further deformation of the mass of granular material by the increased pressure.

4. In a shoe machine, a container inclosing a deformable mass of granular material mingled with a fluid and having a flexible and extensible wall impervious to fluid, means for causing said wall of the container and the mass of granular material to conform to the contour of a portion of a shoe on a last in response to pressure of the shoe thereon and thereafter to press more forcibly on the shoe, a suction pump communicating with said container, and means for starting the operation of said pump after said wall of the container and the mass of granular material have thus conformed to the shoe but prior to such increase of pressure on the shoe to reduce the pressure of the fluid in the container and thereby to prevent further deformation of the mass of granular material.

5. In a shoe machine, a container inclosing a deformable mass of granular material mingled with a fluid and having a flexible and extensible wall impervious to fluid, means for effecting relative movement between said container and a shoe in the machine to cause said wall of the container and the mass of granular material to conform to the contour of a portion of the shoe in response to pressure of the shoe thereon and for thereafter increasing the pressure of said wall on the shoe in the course of a cycle of operations of the machine, a suction pump communicating with said container, an electric motor for operating said pump, and automatic means for starting said motor at a time in the cycle after said wall has thus conformed to the shoe but prior to its increase of pressure on the shoe to reduce the pressure of the fluid in the container and thereby to prevent further deformation of the mass of granular material when the increased pressure is applied.

6. In a shoe machine, a container inclosing a deformable mass of granular material mingled with a gaseous fluid and having a flexible and extensible wall impervious to fluid, means for causing said wall of the container and the mass

of granular material to conform to the contour of a portion of a shoe on a last in response to pressure of the shoe thereon and thereafter to press more forcibly on the shoe, suction means for producing a partial vacuum in the container after said wall and the mass of granular material have thus conformed to the shoe but prior to such increase of pressure on the shoe to prevent further deformation of the mass of granular material, and valve means controlled independently of said suction means for relieving the partial vacuum in the container after the operation of the machine on the shoe.

7. In a shoe machine, a container inclosing a deformable mass of granular material mingled with a fluid and having a flexible and extensible wall impervious to fluid, means for causing said wall of the container and the mass of granular material to conform to the contour of a portion of a shoe on a last in response to pressure of the shoe thereon and thereafter to press more forcibly on the shoe, a suction pump communicating with said container, means for starting the operation of said pump after said wall of the container and the mass of granular material have thus conformed to the shoe but prior to such increase of pressure on the shoe to reduce the pressure of the fluid in the container and thereby to prevent further deformation of the mass of granular material, and means for restoring independently of the pump initial pressure conditions in the container after the operation of the machine on the shoe.

8. In a shoe machine, a container inclosing a deformable mass of granular material mingled with air and having a flexible and extensible wall impervious to air, means for causing said wall of the container and the mass of granular material to conform to the contour of a portion of a shoe on a last in response to pressure of the shoe thereon and thereafter to press more forcibly on the shoe, a suction pump communicating with said container, means for starting the operation of said pump after said wall of the container and the mass of granular material have thus conformed to the shoe but prior to such increase of pressure on the shoe to produce a partial vacuum in the container and thereby to prevent further deformation of the mass of granular material, and valve means for opening the container to the atmosphere to relieve the partial vacuum therein after the operation of the machine on the shoe.

9. In a shoe machine, a container inclosing a deformable mass of granular material mingled with a fluid and having a flexible and extensible wall impervious to fluid, means for effecting relative movement between said container and a shoe in the machine to cause said wall of the container and the mass of granular material to conform to the contour of a portion of the shoe in response to pressure of the shoe thereon, means for thereafter reducing the pressure of the fluid in the container to render the mass of granular material substantially rigid, and means for operating on the shoe while it is controlled by the granular material in that condition.

10. In a shoe machine, a container inclosing a deformable mass of granular material mingled with a fluid and having a flexible and extensible wall impervious to fluid, means for effecting relative movement between said container and a shoe in the machine to cause said wall of the container and the mass of granular material to conform to the contour of a portion of the shoe in response to pressure of the shoe thereon, a suction pump communicating with said container, and auto-

11

matic means for starting said pump after said wall of the container and the mass of granular material have thus conformed to the shoe to reduce the pressure of the fluid in the container and thereby to prevent further deformation of the mass of granular material in the course of the operation of the machine.

11. In a shoe machine, a container inclosing a deformable mass of granular material mingled with a fluid and having a flexible and extensible wall impervious to fluid, means for effecting relative movement between said container and a shoe in the machine to cause said wall of the container and the mass of granular material to conform to the contour of a portion of the shoe in response to pressure of the shoe thereon, a suction pump communicating with said container, means for starting the operation of said pump after said wall of the container and the mass of granular material have thus conformed to the shoe to reduce the pressure of the fluid in the container and thereby to prevent further deformation of the mass of granular material in the course of the operation of the machine, and means for thereafter restoring independently of the pump initial pressure conditions in the container.

12. In a shoe machine, a container inclosing a deformable mass of granular material mingled with air and having a flexible and extensible wall impervious to air, means for moving said container toward a shoe in the machine to cause said wall and the mass of granular material to conform to the contour of a portion of the shoe in response to pressure of the shoe thereon, suction means for thereafter producing a partial vacuum in the container to render said mass of granular material substantially rigid, and a valve affording communication between the interior of the container and the atmosphere when the valve is open, said valve being arranged to close automatically as the container is moved toward the shoe.

13. In a shoe machine, a container inclosing a deformable mass of granular material mingled with air and having a flexible and extensible wall impervious to air, means for moving said container toward a shoe in the machine to cause said wall and the mass of granular material to conform to the contour of a portion of the shoe in response to pressure of the shoe thereon, suction means for thereafter producing a partial vacuum in the container to render said mass of granular material substantially rigid, means providing an open passageway between the interior of the container and the atmosphere when the container is in its initial position, and automatic means for closing said passageway as the container is moved toward the shoe and for opening it again upon return movement of the container.

14. In a shoe machine, a container inclosing a deformable mass of granular material mingled with a fluid and having a flexible and extensible wall impervious to fluid, means for causing said wall of the container and the mass of granular material to conform to the contour of a portion of a shoe on a last in response to pressure of the shoe thereon, a suction pump communicating with said container for reducing the pressure of the fluid therein after said wall of the container and the mass of granular material have thus conformed to the shoe to prevent further deformation of the mass of granular material, and automatic means for starting said pump and for thereafter stopping it in the course of the operation of the machine.

15. In a lasting machine, wipers for wiping the

12

marginal portion of an upper about the toe end of a last inwardly over an insole on the last and for pressing the upper on the insole heightwise of the last, a toe rest for supporting the shoe at the top of the forepart against such pressure of the wipers on the upper, said toe rest comprising a container inclosing a deformable mass of granular material mingled with a fluid and having a flexible and extensible wall impervious to fluid for engaging the upper, means for effecting relative movement between the shoe and the toe rest to cause said wall of the container and the mass of granular material to conform to the contour of the shoe in response to pressure of the shoe thereon, and means for thereafter reducing the pressure of the fluid in the container to prevent further deformation of the mass of granular material by the pressure of the wipers on the shoe.

16. In a lasting machine, wipers for wiping the marginal portion of an upper about the toe end of a last inwardly over an insole on the last and for pressing the upper on the insole heightwise of the last, a toe rest for supporting the shoe at the top of the forepart against such pressure of the wipers on the upper, said toe rest comprising a container inclosing a deformable mass of granular material mingled with a fluid and having a flexible and extensible wall impervious to fluid for engaging the upper, means for moving said toe rest toward the shoe to cause said wall of the container and the mass of granular material to conform to the contour of the shoe in response to pressure of the shoe thereon and for thereafter increasing the pressure of the toe rest on the shoe, and means for reducing the pressure of the fluid in the container after said wall and the mass of granular material have thus conformed to the shoe but prior to the increase of pressure of the toe rest on the shoe to prevent further deformation of the mass of granular material when such increased pressure is applied.

17. In a lasting machine, wipers for wiping the marginal portion of an upper about the toe end of a last inwardly over an insole on the last and for thereafter applying increased pressure to the upper heightwise of the last, a toe rest for supporting the shoe at the top of the forepart against the pressure of the wipers on the upper, said toe rest comprising a container inclosing a deformable mass of granular material mingled with a fluid and having a flexible and extensible wall impervious to fluid for engaging the upper, means for effecting relative movement between the shoe and said toe rest to cause said wall of the container and the mass of granular material to conform to the contour of the shoe in response to pressure of the shoe thereon prior to the wiping of the upper inwardly over the insole, and means for reducing the pressure of the fluid in the container after the wipers have wiped the upper inwardly but prior to their increase of pressure on the upper to prevent further deformation of the mass of granular material when such increased pressure is applied.

18. In a lasting machine, wipers for wiping the marginal portion of an upper about the toe end of a last inwardly over an insole on the last and for thereafter applying increased pressure to the upper heightwise of the last, a toe rest for supporting the shoe at the top of the forepart against the pressure of the wipers on the upper, said toe rest comprising a container inclosing a deformable mass of granular material mingled with a fluid and having a flexible and extensible wall impervious to fluid for engaging the upper,

75

13

means for moving said toe rest toward the shoe to cause said wall of the container and the mass of granular material to conform to the contour of the shoe in response to pressure of the shoe thereon, additional means for thereafter forcing the toe rest more firmly against the shoe to support the shoe against the increased pressure of the wipers on the upper, and means for reducing the pressure of the fluid in the container after

14

5 said wall and the mass of granular material have thus conformed to the shoe but prior to the action of said additional means on the toe rest to prevent further deformation of the mass of granular material when the increased pressure is applied to the upper by the wipers.
